[57] CLAIM

The ornamental design for a solid state protector for communications circuits or similar article, substantially as shown and described.

DESCRIPTION

FIG. 1 is an isometric view of a solid state protector for communications circuits or similar article showing my new design.

FIG. 2 is a top plan view thereof.

FIG. 3 is a side view of the solid state protector for communications circuits or similar article, the other side view being a mirror image thereof.

FIG. 4 is an end elevation of the solid state protector for communications circuits or similar article, the opposite end elevation being a substantial duplicate thereof.

FIG. 5 is a bottom plan view of the solid state protector for communications circuits or similar article.
